UNITED STATES PATENT OFFICE.

JAMES ALFRED SCOTT, OF BOSTON, MASSACHUSETTS, ASSIGNOR OF ONE-HALF TO CHARLES E. FULLER, OF SOMERVILLE, MASSACHUSETTS.

FOLDING PAPER BOX AND BLANK THEREFOR.

SPECIFICATION forming part of Letters Patent No. 655,521, dated August 7, 1900.

Application filed September 18, 1899. Serial No. 730,840. (No model.)

To all whom it may concern:

Be it known that I, JAMES ALFRED SCOTT, of Boston, in the county of Suffolk and State of Massachusetts, have invented certain new and useful Improvements in Folded Paper Boxes and Blanks Therefor, of which the following is a description sufficiently full, clear, and exact to enable those skilled in the art to which it appertains or with which it is most nearly connected to make and use the same.

This invention has relation to folded paper boxes and box-blanks for the manufacture of the same.

It is the object of the invention to provide such improvements in the articles mentioned as will enhance the readiness with which they may be folded, increase the strength of the box, and effect the more secure holding together of the parts.

The invention consists of a box-blank and box having structural characteristics and features in virtue of which improved and beneficial results are accomplished, as is herein-after set forth in detail.

Reference is to be had to the annexed drawings, which show forms of box-blanks and boxes which may embody my improvements, the same letters designating the same parts or features, as the case may be, wherever they occur.

Of the drawings, Figure 1 is a view of one end of a box-blank developed embodying the invention. Fig. 2 shows the blank illustrated in Fig. 1 as folded into box form. Fig. 3 is a view similar to Fig. 1, but showing the side ends slightly modified in form. Fig. 4 shows the blank illustrated in Fig. 3 as folded into box form. Fig. 5 is a view similar to Figs. 1 and 3, but showing the side ends as extended so as to reach across the end of the box and slotted to receive through them the latching-tab. Fig. 6 shows the blank illustrated in Fig. 5 as folded into the form of a box. Figs. 7 and 8 show modified forms, described hereinafter.

In the drawings, *a* designates the part of the blank forming the bottom, *b b* the sides, and *c* the ends, of the box. The lines upon which the folds are made are dotted in the figures designating the blanks.

d designates a tab, herein termed the "latch-

ing-tab," which in all cases is formed out of the end portions *c*, the upper part of each of which is extended to form the locking fold *e*.

ff designate the foldable end parts of the sides, which parts in the developed blanks extend parallel with the ends *c*, but are separated therefrom by cuts *g g*.

In Figs. 1 and 2 (and it may be the case with other forms) the ends of the sides *b* adjacent to the foldable end parts *f* and the latter are widened, as at *h h*, beyond the width of the main portions of the sides, so as to be turned down, as shown in Fig. 2, for the purpose of strengthening the box-corners. 65

The foldable end parts *ff* in Figs. 1 and 2 are made just long enough to bring their edges *i*, when they are folded, up to the sides of the tab *d*, so that when the locking fold *e* is folded from the position shown in Fig. 1 to 70 that shown in Fig. 2 it will not only be in position to be tucked in behind the latching-tab *d*, but will engage and hold the upper ends of the foldable parts *ff*.

In Fig. 3 the end parts *f* are extended at 75 their outer sides, as at *j*, so that when the said end parts are folded in to form a box, as shown, the extensions *j* will overlap above the tab *d* and the locking fold *e* will be folded over them, and so strengthen the end of the 80 box. In this case the inner sides of the extensions *j* may be beveled, as at *k*, so as to extend slightly under the tabs *d*.

In Figs. 5 and 6 I have shown the end parts *f* as of full width and extended, so that when 85 folded in they will each cover the entire end of the box. In this case the extensions are slotted, as at *l*, so that the latch-tab *d* may be pushed therethrough, as shown in Fig. 6, and the locking fold *e* then tucked in behind the 90 tab and the whole held in place by the locking fold. These and other variations may be made in the form and arrangement of parts constituting my invention without departing from the nature or spirit thereof. 95

It is to be noted that the cover for the box may be made in the same way as the box itself.

In Fig. 7 I have shown a form of blank which may be employed, as illustrated in Fig. 8, to 100 form a large box—such, for example, as those in which tailors pack clothing for transporta-

tion. In this case the end piece *c*, near each corner, is provided with a tab *d*, and there are extensions *e* on the ends above each tab serving as locking folds. The end extensions *f* of the sides *b* are slotted, as at *l*, as is the case with the constructions shown in Figs. 5 and 6. In this case the extensions will be folded down and the slots *l* engaged with the tabs *d*, and then the locking folds are folded over behind the tabs, securing the parts in place. In this case the latching-tab is provided with an offset *m* to catch against the edge of the slot and hold the side from being pulled outward.

In every form shown it will be observed that the latching-tabs are accessible from the exterior of the box, which circumstance greatly facilitates manipulation in putting the box together, when it is necessary that the said tabs be pushed inwardly, while the locking folds are being turned down for engagement therewith. Another advantage of having the latching-tabs in those end portions of the box which fold up from the bottom is that a much shallower box or cover can be made, since the latching-tabs can be located very close to the bottom of the box.

Having thus explained the nature of the invention and described a way of constructing and using the same, though without attempting to set forth all of the forms in which it may be made or all of the modes of its use, it is declared that what is claimed is—

1. In a folded paper box, the combination of a bottom, a side folded up from the same and having an end portion folded in so as to extend across above the bottom, and an end folded up from the bottom outside said side end portion and having an incision forming an upstanding latching-tab protruding inward past the latter and manipulative from the exterior of the box through the incision, said end having an extension constituting a locking fold turned down over the side end portion and entered behind the latching-tab, substantially as described.

2. In a folded paper box, the combination of a bottom, a side folded up from the same and having an end portion folded in so as to extend across above the bottom, and an end folded up from the bottom outside said side end portion and having an incision forming an upstanding latching-tab protruding inward past the latter and manipulative from the exterior of the box through the incision, said end having an extension constituting a locking fold turned down over the side end

portion and entered behind the latching-tab, and the side end portion also being engaged behind said tab, substantially as described.

3. In a folded paper box the combination of a bottom portion, an end portion folded up from the latter and having an upstanding latching-tab and an extension constituting a locking fold turned in over the end portion and engaged behind the latching-tab thereof, and a side portion folded up from the bottom and having an end extension folded in between the end portion of the box and the locking fold and having a slot through which the latching-tab extends, substantially as described.

4. A folded paper box comprising bottom, end, and side portions, the latter and the end portions being folded up from the bottom portion, the side portion having overlapping end extensions folded in over the bottom portion, and the end portions having upstanding latching-tabs extending over the end extensions of the side portions, said end portions also having extensions constituting locking folds turned down over the said end extensions of the side portions and engaged behind the latching-tabs.

5. A folded paper box comprising bottom, end, and side portions, the latter and the end portions being folded up from the bottom portion, the side portions having overlapping end extensions folded in over the bottom portion and formed with registering slots, and the end portions having upstanding latching-tabs extending through the registering slots of the end extensions of the side portions, said end portions also having extensions constituting locking folds turned down over the said end extensions of the side portions and engaged behind the latching-tabs.

6. A foldable-paper-box blank comprising a bottom portion, side portions with end extensions or folds, and end portions with abbreviated extensions constituting locking folds and formed with latching-tabs directed outwardly for engagement behind them of the locking folds when the latter are folded in over the side end folds.

In testimony whereof I have signed my name to this specification, in the presence of two subscribing witnesses, this 16th day of September, A. D. 1899.

JAMES ALFRED SCOTT.
